[57] CLAIM

The ornamental design for a fireplace insert smoke pipe connector, as shown and described.

DESCRIPTION

FIG. 1 is a top, front perspective view of a fireplace insert smoke pipe connector, showing my new design; FIG. 2 is an enlarged top plan view thereof; FIG. 3 is an enlarged rear elevational view thereof; FIG. 4 is an enlarged bottom plan view thereof; FIG. 5 is an enlarged side elevation view thereof, the opposite side being a mirror image of that shown; FIG. 6 is an enlarged front elevational view thereof; and FIG. 7 is an enlarged top, front perspective view thereof.

The broken line showing of environmental structure in FIG. 1 is for illustrative purposes only and forms no part of the claimed design.

FIG. 3

FIG. 4

FIG. 5

FIG. 6

FIG. 7
